PHOTOCELL

Zen-Ichi Kamayachi and Kenichi Ishii, Shibaku,
Tokyo, Japan, assignors to International
Standard Electric Corporation, New York, N. Y.,
a corporation of Delaware

Application September 12, 1939, Serial No. 294,510
In Japan October 5, 1938

1 Claim. (Cl. 136—89)

This invention relates to a photocell which is formed by applying a selenium semi-conductor upon the surface of a base electrode plate by coating a thin film of a fourth-group metal such as tin, lead etc. upon the surface thereof and still more by coating a thin film of platinum, silver etc. thereupon. Its object is to obtain a photocell which is excellent in sensitivity.

The drawing is a view showing the construction of a sensitive element in the photocell of this invention.

This invention is related to the improvement of a photocell using a selenium semi-conductor.

In a photocell of this type practiced heretofore, it is formed by having a selenium semi-conductor 15 applied upon a base metallic plate and by having a thin film of platinum, silver, copper etc. coated upon the surface thereof.

We produce a photocell by first applying a thin film of a fourth-group metal such as a tin etc. 20 upon a selenium semi-conductor which had been applied to a base electrode by a spraying or distillation method, and then by coating a thin film of platinum, silver etc. upon the surface of said film by a similar method. The photocell thus obtained is striking and excellent in its photoelectric effect.

Reference numeral 1 shows a base electrode, usually an iron plate the surface of which is made mechanically coarse. If required, 1 may 30 be provided with a plating of nickel, cobalt etc.

Reference numeral 2 shows a layer of selenium semi-conductor formed by heating a base iron plate to a given temperature for a fixed time prior to its application, by having a molten selenium applied or sprayed thereto and still more by heating it at a normal temperature for a fixed 35

time under pressure, thereby constructing a selenium semi-conductor having a thickness uniform in sensitivity.

Reference numeral 3 shows a thin film in which one or several kinds of a fourth-group metal had been attached upon the surface of the selenium by a spraying or distillation method.

Reference numeral 4 is a platinum or silver coating. It is necessary that the thin films composed of the layers (3) (4) are of suitable thickness so as to allow a large amount of light to get to the selenium semi-conductor. The sensitive element is then mounted by pressing electrodes consisting of a copper ring etc. against the upper electrode and the base electrode, respectively. To protect the upper electrode, a glass plate or transparent lacquer etc. is provided for the purpose of the mechanical as well as the chemical protection of the sensitive element.

It is to be understood of course that although the invention has been described in connection with tin and lead as possible fourth group metals for the layer 3, others may be employed, such as titanium, germanium, zirconium, cerium, silicon, and thorium.

What is claimed is

A photocell which comprises a base electrode plate, a coating of a selenium semi-conductor thereon, a thin film of at least one of the metals belonging only to the fourth group of the periodic table of elements on the exposed surface of said selenium semi-conductor coating, and a transparent film of a substantially chemically inert metal coated on the exposed surface of said thin film.
